UNITED STATES PATENT OFFICE

2,060,599

HEATING UNIT FOR COMBUSTION CHAMBERS

Ray F. Van Seggern, New Brunswick, N. J.

Application March 23, 1933, Serial No. 662,403

16 Claims. (Cl. 122—210)

The present invention relates to improvements in heating unit for combustion chambers, and more particularly relates to a water heater constructed and adapted for placement in the fire box of a steam boiler.

It is an object of the invention to provide an improved water heating unit having numerous water circulating pipes of small diameter yielding a large surface area to the products of combustion whereby the water may be rapidly and instantaneously heated and flashed into steam.

Another object of the invention is to provide an improved heating unit of a simple and compact construction, economically manufactured and of a form suitable for introduction in sections into existing forms of furnaces without requiring the disassembling of any part of the furnace wall, such units of the improved device being easily and readily assembled in the fire box to constitute a heater of extremely high efficiency.

The invention also consists in certain new constructions involving the formation of the headers, of the arrangement of the water pipes and of the delivery pipe for delivering the water and steam into the steam dome of the boiler.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a fragmentary perspective view of a boiler showing the improved heating unit in the combustion chamber thereof.

Figure 2 is a central vertical section taken longitudinally through a portion of the boiler and through the improved heating unit.

Figure 3 is an enlarged end view of the heating unit removed from the boiler.

Figure 4 is a vertical section taken on an enlarged scale on the line 4—4 in Figure 3.

Figure 5 is a section taken on the line 5—5 in Figure 4.

Figure 6 is an end view of Figure 5, and

Figure 7 is an enlarged fragmentary section through one of the push nipple assemblies.

Referring more particularly to the drawings, 50 10 designates generally a heating boiler of any conventional type having a customary brick work 11 in the combustion chamber thereof; the vertical flue passage 12 at the back of the combustion chamber; horizontal flue passages 13; and 55 the steam dome 14 from which the steam gen-

erated in the boiler may pass up through the riser 15 to the radiators of the building or to some other destination.

The oil burner for heating the boiler is introduced at the point indicated at 16 though the boiler may be fired by other means if desired. The fire door is indicated at 17.

The improved heating unit may be introduced in sections through the fire door 17, and assembled within the combustion chamber. The unit 10 preferably is adapted to rest freely upon the brick work 11. No modification of the conventional furnace or boiler is in any way required.

The improved heating unit in that form there- 20 illustrated in the figures of the drawings is 15 constructed of two lower headers A and B and of an upper central header C, thus giving to the unit a form generally triangular as may be seen in Figure 3. Between the headers are groups of 25 pipes of small diameter through which the water may be circulated, these pipes having a peculiar arrangement as hereinafter more fully described. The headers are built up substantially alike, and as shown in Figures 2, 5, 6, and 7, such headers are composed of a plurality of tubular sections 18. These pipes or sections are formed with en- 30 larged ends 19. As shown in Figure 7, the ends of adjacent sections 18 are brought together in abutting relation and form a push nipple as- 35 sembly with a ring 20, which ring has a rounded outer surface upon which the rounded inner walls 21 may be forced. Pipe joint compound or other similar leak proofing material, indicated at 22, is placed between the ends 19 and between the ring 20 and the surfaces 21.

The act of forcing the end portions 19 of the two sections in opposite directions on the ring 20 will cause the compound material to come together at the base of the joint between the two heads 19 and flow out between such heads and thereby 40 form an effective seal. The two heads 19 will be urged firmly into engagement with the ring 20 and make a very tight and effective union. These heads or end portions 19 are provided with bevelled portions, as clearly shown in Figure 7, where- 45 by an extra amount of pipe compound may be received between two adjacent end portions to seal the same and assure a water tight joint.

The headers may be composed of any desired number of the sections 18 in accordance with the 50 size of heating unit desired. All of these sections are firmly bound together, as shown in Figure 2, by a threaded rod 23 passing axially in common through the sections and having the ends thereof threaded into end caps 24 and elbows 55

25. The cap 24 is provided with a number of bosses or raised surfaces to take a wrench. This end cap and elbow encloses the ends of the headers. The rear elbow 25 of the upper header forms a connection for the steam and hot water pipe 26. This steam and hot water rises through the back vertical flue 12, passes along in a pipe 27 through horizontal flue 13 and out the front cleanout door of the boiler, thence upwardly, as indicated at 28, and again entering the boiler at the steam dome extending inwardly, and terminating within the steam dome.

Such pipe has a horizontal discharge end portion 29 in the steam dome having its open end disposed remote from the riser or risers. The saturated steam is thus kept from ascending through the riser 15, which would cause trouble in the heating plant.

The discharge end of pipe 29 is split or cut away as to its lower half portion throughout a part of the length of such pipe in the delivery end. Such removed portion is indicated at 30. This leaves only the upper half section. The removed part permits the separation of the water while the steam passes along under the unremoved portion of the pipe and is not liberated until such steam passes off beyond such unremoved upper portion of the pipe. In this way the water and steam are separated, the water being allowed to drop down returning to the boiler water in the sections of boiler 10.

Between the various headers are groups of pipes of small diameter. These groups are secured into the flat walls 31 of the header section 18. These pipes or tubes 32 are not threaded outwardly, as indicated at 33, such swaged ends being seated upon bosses 34 of the header section. Such bosses are within internally threaded sockets 35 adapted to receive the externally threaded bushings 36 which surround the tubes 32 and press the swaged ends 33 of the tubes against the seats 34.

It is to be noted that the bushings 35 have male rather than female threads and that the bushings have castellated heads 37 whereby a spanner wrench may engage over or about the pipes 32 for getting at the bushings to tighten same. The arrangement allows the bushings to be received into the threaded socket 35 in the header sections whereby the bushing is for a considerable part within the protection of the heavy metal section of the water containing headers. Consequently, the entire bushing is not directly exposed to the intense heat of the products of combustion. Furthermore, expansion of the bushing when heated results in a tighter joint between the bushing and header and the tube secured in position by the bushing. For this reason, the construction overcomes any possibility for leakage to occur even when the bushings are subjected to very intense heat.

As shown in Figure 4, ten of the small pipes 32 are adapted to be connected into a header section 18. Each header section 18 of the upper header C receives ten of the pipes. One section will receive these ten pipes at one side thereof, while the adjacent sections 18 at opposite sides of the first mentioned sections receive the pipes 32 upon the opposite side thereof. These pipes extend out from the connected upper header section for a distance almost horizontally, they being curved downwardly and inwardly and caused to follow a substantially diagonal path down to the lower headers A and B. Thus the pipes 32

are divided into groups. In the present case these groups consist of ten pipes, as shown in Figure 4.

One group connects at its upper end upon one side of the header C, passes down diagonally in one direction and joins with a section 18 of the lower header A. The next adjacent group of pipes 32 extends outwardly from the upper header C but in an opposite direction from the first group of pipes and thence extends down diagonally but in an opposite sense from the first group of pipes and crossing the first group of pipes intermediate the diagonal length of the same, whereby such second group of pipes arrives at the other lower header B. In this way the groups of pipes alternate in direction and in connection with the headers A and B.

The arrangement is clearly shown in Figure 1. Certain of the header sections 18 of the lower headers A and B are without any pipe connections, such header sections alternating with those which receive the pipes 32. The arrangement provides a desired number of groups of numerous pipes of small diameter exposed throughout a large surface area to the flame and products of combustion in the combustion chamber, such products of combustion readily passing up along the diagonal reaches of the pipes and rapidly heating the small cross section thereof with the contained water. Such numerous pipes of small diameter in the arrangement shown enable a flash or quick steaming action to be obtained.

The unit takes on the cooler portions of the boiler water and rapidly injects heated water and steam into the upper section of the boiler, and thus materially increases the circulation in both the boiler and the entire heating system connected to the boiler.

The headers A and B are connected by a pipe 38, and this pipe connects with a water inlet pipe 39, which may be introduced through any of the ash pit walls of the furnace without requiring any alteration of the furnace other than to make an opening through the metal wall, which does not contain water, and permits the passage of the pipe. The unit is not rigidly fastened in the combustion chamber of the boiler but rests on the brick work 11, allowing for free expansion and contraction of the unit.

The shape of the unit is such as to permit the free travel of the flue gases and elements of combustion without causing choking of the flames by the tubes. The construction allows the flue gases to pass over, under, through and around the small copper pipes 32.

While the tubes have been shown in rectangular arrangement they may assume various different shapes and arrangements. Furthermore the heating unit may be made up of a series of four or any other number of headers with the copper tubes connecting these headers. The location of the upper headers may vary in various installations and the shape and form of the numerous types would vary depending upon the boiler itself.

In practice in making installations it has been found preferable in some cases to make the pipe connections to the lower headers through the front of the boiler rather than through the rear thereof. It has also been found that if the pipe connections 38 and 39 are transferred to the front sections of the headers A and B that this rearrangement has certain and distinct advantages over the connection in the rear. One advantage is that it insures a supply of water more direct to

the front sections, which are located in the zone of highest temperature. The incoming water is also caused to flow from the front of the lower headers through the various tubes to the rear of the upper header insuring effective circulation throughout the entire unit. Therefore, while we show in the drawings the pipes 38 and 39 as connected to the rear ends of the headers A and B, such pipe connections may be coupled to either end of the headers A and B as the caps 24 and the elbows to which pipe 38 is connected are interchangeable. The pipe connections to the top or upper header C are also interchangeable. In other words the general assembly is flexible so that the device may be adapted to any type or size of boiler and may be readily assembled within the boiler without dismantling the boiler. Furthermore, in the event it is found that any installation should be made larger or smaller or it is necessary to remove or replace any of the tubes or header sections, this may be easily and quickly accomplished without removing or discarding other elements of the construction. The flexibility of construction and the adaptability of the unit and the various parts making up the same render the invention of particular value. It is not necessary to keep a large variety of sizes, styles and shapes of parts in stock to enable the dealer to install, repair, or alter the units. The use of standardized parts, suitable for use in a wide variety of sizes and arrangements of heating units, renders it possible to apply units to either new or existing boiler installation with a minimum amount of trouble and expense.

35 The rods 23 are internal of the sections and therefore surrounded by water, thus eliminating entirely the excessive expansion and contracting which would occur if the rods were not protected by water from the products of combustion.

40 It will be obvious that various changes in the construction, combination and arrangement of parts could be made which could be used without departing from the spirit of my invention, and I do not mean to limit the invention to such details, except as particularly pointed out in the claims.

Having thus described my invention, what I claim and desire to secure by Letters Patent of the United States is:—

1. In combination with a boiler having a riser through which a heating medium passes from the boiler, an improved heating unit located in the combustion chamber of the boiler, a hot water and steam pipe leading from said heating unit and entering the dome of the boiler horizontally, said pipe having its delivery end remote from the riser and cut away as to its under portion for an appropriate length to provide for the separation of water and steam.

2. A unit adapted to be applied to existing boilers which have an outlet for the passage of a heating medium therefrom, which unit serves to increase the absorption of heat from flame and products of combustion passing through the combustion chamber, comprising a plurality of header sections each capable of being introduced into the combustion chamber through the usual fire door and assembled within the boiler to form a completed header, a plurality of heating tubes connected to said header and means providing communication between the lower portion of the boiler and said heating tubes and a conduit communicating with said completed header connected to the exterior of the boiler at a point spaced from the boiler outlet to provide a path for the flow of water from the lower portion of said

boiler through said unit to the upper portion of said boiler.

3. A unit adapted to be applied to existing boilers to increase the absorption of heat from flame and products of combustion passing through the combustion chamber comprising a plurality of groups of elements, each of which groups includes a section of an upper header, a section of a lower header and heating tubes extending between said header sections, said groups of elements being assembled with connecting elements to form a heating unit including a common completed upper header and spaced lower headers and conduits connected to the boiler and extending through unjacketed portions thereof to said headers. 15

4. A unit adapted to be applied to existing boilers to increase the absorption of heat from flame and products of combustion passing through the combustion chamber comprising a plurality of groups of elements, each of which groups includes a section of an upper header, a section of a lower header and heating tubes extending between said header sections, said groups of elements being assembled with connecting elements to form a heating unit including completed upper and lower 25 headers and spaced oppositely extending tubular means communicating with said upper and lower headers and connected with a portion of the boiler which is not exposed to direct heat from flames and products of combustion to provide a path for 30 the flow of water from the lower portion of said boiler through said unit to the upper portion thereof.

5. In combination with a boiler having a combustion chamber and at least one substantially 35 horizontal flue pass for the flow of the products of combustion from the combustion chamber over the boiler to the stack and having an outlet for the passage of a heating medium from the boiler, a heating unit located in the combustion chamber of the boiler, means for circulating water from the lower portion of said boiler through said heating unit and into the upper portion of the boiler, said means including a conduit extending through said flue pass and out through an unjacketed member to a point in the upper portion of said boiler spaced from said outlet. 40 45

6. In combination with a boiler having a combustion chamber and at least one flue pass above the lowermost crown sheet of the boiler for the flow of the products of combustion from the combustion chamber over the boiler to the stack, a heating unit located in the combustion chamber of the boiler, means for circulating water from the lower portion of said boiler through said heating unit and into the upper portion of the boiler, said means including a conduit extending through said flue pass and out through a cleanout door above the lower-most crown sheet of the boiler to the upper portion of the boiler. 50 55

7. In combination with a boiler having a combustion chamber and one or more flue passes for the flow of products of combustion from the combustion chamber over the boiler and to the stack and having an outlet for the passage of a heating medium from the boiler, a heating unit serving to increase circulation of the boiler water located in the combustion chamber comprising a plurality of heating tubes, a portion of which have the lower ends thereof connected to one lower header and others of which have the lower ends thereof connected to another lower header both of which headers are in communication with the lower portion of the boiler, the upper ends of said tubes communicating with a common upper 60 65 70 75

- header, and a conduit extending from said header through at least one of said flue passes and connected to the upper portion of the boiler at a point spaced from the outlet opening.
8. The combination of a boiler having a combustion chamber and one or more flue passes for the flow of products of combustion from the combustion chamber and over the boiler to the stack, and having an outlet for the passage of a heating medium from the boiler and a heating unit serving to increase circulation of the boiler water separably connected to the boiler comprising a plurality of heating tubes located in the combustion chamber and communicating with a header in the upper portion of the combustion chamber, means for supplying boiler water to said tubes and tubular means extending through at least one of said flue passes and providing communication between said header and a point in the upper portion of the boiler spaced from the boiler outlet.
9. In combination with a boiler having an outlet for the passage of a heating medium therefrom, the combustion chamber of which boiler is designed for use with solid fuel but is fired by an oil burner, a supplemental heating unit adapted to be located in the combustion chamber and connected to the boiler to increase the efficiency thereof, said unit comprising lower headers located on each side of the oil burner, a common upper header located above said oil burner, heating tubes extending in opposite directions from said upper header and connected to said lower headers and means communicating with said upper header connected to the exterior of the boiler at a point spaced from the boiler outlet and other means communicating with said lower headers and the lower portion of the boiler to form a path for the circulation of boiler water through said unit.
10. In combination with a boiler having an outlet for the passage of a heating medium therefrom, the combustion chamber of which boiler is designed for use with solid fuel but which is fired by an oil burner, a supplemental heating unit adapted to be located in the combustion chamber and connected to the boiler to increase the efficiency thereof, said heating unit comprising a header located in the combustion chamber, a plurality of heating tubes connected to said header, and means connected to said header extending through an unjacketed portion of the boiler and connected to the exterior thereof at a point spaced from the boiler outlet and other means also extending through an unjacketed portion of the boiler providing communication between the lower portion of the boiler and said heating tubes to form a path for the circulation of boiler water through said unit.
11. In combination with a boiler the combustion chamber of which is designed for use with solid fuel but which is fired by an oil burner, a supplemental heating unit adapted to be located in the combustion chamber and connected to the boiler to increase the efficiency thereof, said heating unit comprising a plurality of groups of elements each of which groups includes a section of an upper header, a section of a lower header and heating tubes extending between said header sections, said groups of elements being assembled with connecting elements to form a heating unit including completed upper and lower headers and means connected to said upper and lower headers and extending through unjacketed portions of the boiler to the exterior thereof to form a path for the circulation of boiler water through said unit.
12. A heating unit adapted to be located in the combustion chamber of a boiler comprising a plurality of groups of elements each embodying two header sections and one or more heating tubes communicating with said sections, said groups being assembled with one header section of each group forming a portion of a common header and with the other header section of each group assembled with connecting elements and forming a portion of one of a plurality of other headers, and means providing communication between all of said headers and the boiler for effecting circulation of boiler water through said unit.
13. A heating unit adapted to be located in the combustion chamber of a boiler comprising a plurality of groups of elements each embodying an upper header section, a lower header section and one or more heating tubes communicating with said sections, said groups being assembled with the upper header section of each group forming a portion of a single upper header and with the heating tubes of others of said groups extending from the upper header at an angle to the heating tubes of others of said groups, the lower header sections being assembled with connecting elements to form spaced lower headers, and means providing communication between all of said headers and the boiler for effecting circulation of boiler water through said unit.
14. A heating unit adapted to be located in the combustion chamber of the boiler comprising an upper header section, a lower header section and one or more heating tubes communicating with said sections, said groups being assembled with the upper header sections of each group connected to form a single upper header and with the heating tubes of adjacent groups extending in opposite directions from the upper header, the lower header sections of said groups being assembled with connecting elements to form spaced lower headers, and means providing communication between all of said headers and the boiler for effecting circulation of boiler water through said unit.
15. In combination with a boiler having downwardly extending water legs, an ash pit located below the bottom of the water legs and a combustion space extending above the bottom of the water legs, an oil burner discharging flame and products of combustion into the ash pit from which they pass through said combustion space, a supplemental heating device through which boiler water is circulated having a hollow water receiving body located in the combustion space above the bottom of the water legs and extending transversely of the path of flow of flame and products of combustion through the combustion space and connections for completing a circuit for the flow of boiler water through said device including a conduit connected to the exterior of the boiler near the bottom of said water legs and passing into the ash pit and below the bottom of the water legs to the lower portion of said supplemental heating device and another conduit passing from the upper portion of the supplemental heating device through an unjacketed portion of the boiler above the bottom of the water legs and connected to the upper portion of the boiler.
16. In combination with a boiler having a combustion space and water legs extending down-

- wardly about the same, refractory material located below the water legs and an oil burner discharging flame and products of combustion against said refractory material from which they 5 pass through said combustion space, a supplemental heating device located in part at least above the bottom of said water legs and above said refractory material, said device comprising a hollow water receiving body through which 10 boiler water is circulated formed with spaced water receiving portions extending transversely of the path of flow of flame and products of combustion through the combustion space and con-
- nections between the device and boiler completing a circuit for the circulation of boiler water therethrough including a conduit extending from the exterior of the lower portion of said water legs and passing through an unjacketed portion 5 of the boiler below the water legs to the lower portion of said device and another conduit extending from the upper portion of the device through an unjacketed portion of the boiler above the bottom of the water legs and connected to 10 the upper portion of the boiler.

RAY F. VAN SEGGERN.
